UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

Application filed May 4, 1923. Serial No. 636,557.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanism for looms whereby the filling is replenished from time to time while the loom continues to run.

It is now the common practice to wind the filling or weft thread upon the filling carrier or bobbin in conical wind formations known as "filling wind." Should the feeler encounter the conical formation of the filling wind on a detecting beat, it is liable to be given its movement to effect replenishment of filling prematurely and while there still remains within the shuttle a working supply of filling. This objectionable condition is most clearly manifested in that type of feeler mechanism wherein the feeler is mounted to enter the shuttle in a direction inclined to the longitudinal axis of the shuttle, although it may take place in feeler mechanisms of other types.

Should the feeler call for a change of filling prematurely, objectionable waste of filling is liable to occur, while on the other hand if the feeler fails to call for a change of filling when the filling is substantially exhausted on a detecting beat, defective cloth is liable to be produced.

One of the objects of the present invention, therefore, is to provide a feeler mechanism which will be prevented from effecting replenishment of filling while there still remains within the shuttle a working supply of filling, and to permit the feeler to call the change of filling when the filling is substantially exhausted on a detecting beat.

In accordance with the present invention, the feeler mechanism comprises two feelers, both of which enter the shuttle on a detecting beat and feel for the filling, one of the feelers being constituted as a main feeler and the other as an auxiliary feeler for controlling the filling replenishing movement of the main feeler and prevent premature change of filling, and yet permit such change of filling when the filling in the shuttle has become substantially exhausted.

The invention will best be made clear from the following description and accompanying drawings of one good practical form thereof, the novel characteristics and features of which and new combination of parts will be definitely set forth in the claims.

In the drawings:

Fig. 1 is a top perspective view showing a feeler mechanism containing the present invention and sufficient portions of the loom to make clear its construction and mode of operation;

Fig. 2 is an enlarged detail in plan view showing the action of the feeler mechanism when the feelers have presented for their engagement a cylindrical portion of a working supply of filling on a detecting beat;

Fig. 3 is a rear view showing more particularly the details of the two feelers and their respective mountings;

Fig. 4 is a plan view showing the two feelers as having engaged the cylindrical portion of a working supply of filling and the lay in substantially its front position;

Fig. 5 is a view similar to that of Fig. 4 showing a conical portion of filling presented to the filling engaging end of the main feeler and filling of greater diameter engaging the end of the auxiliary feeler;

Fig. 6 is a detail view in plan showing the main feeler as having called for a change of filling when the filling is substantially exhausted.

The advantages of the present invention are best manifested in connection with a main feeler of the side swipe type; i. e., one in which the feeler is moved in a direction longitudinally along the filling carrier to call for a change of filling, and in the present instance such main side swipe feeler is shown as of the inclined type, but the advantages of the invention may be secured in feeler mechanisms of other constructions.

The loom frame has extending from it at one side the shipper stand 1 provided with a slot 2 in which the shipper 3 is movable to start and stop the loom. Mounted upon the shipper stand 1 is the feeler stand 4 which may be formed as a plate provided with an opening 5 through which passes the adjusting bolt or screw 6 for securing the feeler stand in proper position, as usual in this class of looms.

The main feeler 7, herein shown as of

the inclined type, is mounted upon the feeler stand 4, and in the present instance the front end portion of the feeler 7 extends through a swivel bearing 8 mounted in a bracket 9 secured to the feeler stand. The rear portion of the feeler stand is provided with a transversely extending guideway 10 for a laterally movable slide 11, Fig. 3, which is provided with an opening 12 through which the feeler 7 extends. The slide 11 may be retained in its guideway by a cap plate 13 secured to the rear portion of the feeler stand by screws or bolts 14, and the slide 11, in the present instance, is shown as provided with a lug 15 to which is connected the transmitter 16.

The feeler 7 has secured to it a bridge or guide 17 between which and the front bearing 8 is a spring 18 which normally acts to impel the feeler 7 rearwardly, with permissive movement frontwardly. The parts so far described may be of the same general construction and mode of operation as more fully shown and described in the patent to 25 Edward S. Stimpson, No. 1,309,226, dated July 8, 1919, and as in said patent, the feeler 7 is provided with a toothed filling engaging end portion 19. The construction is such that on each detecting beat when a 30 working supply of filling is present in the shuttle and the cylindrical portion thereof is presented to the main feeler, the toothed filling engaging end 19 will sink into the mass of filling and hold the feeler from its 35 side swipe movement, or movement longitudinally along the filling carrier until the filling is substantially exhausted on a detecting beat.

In accordance with the present invention, 40 an auxiliary feeler is provided which enters the shuttle and feels for the filling on each detecting beat, and a locking device between the main and auxiliary feelers serves to prevent side swipe movement of the main 45 feeler in case the diameter of the filling in the shuttle, which is presented to the main feeler, is less than the diameter of the filling in the shuttle presented for engagement by the auxiliary feeler, but frees the main feeler to its side swipe movement should the diameter of the filling presented to the main and auxiliary feelers be the same. In other words, should the auxiliary feeler first engage the filling in the shuttle, it will control the locking device to prevent side swipe 50 movement of the main feeler on a detecting beat, but should the main feeler first be moved frontwardly by engagement with the filling, the locking device is rendered ineffective to prevent side swipe movement of the main feeler.

The auxiliary feeler 20 is shown as mounted for movement towards and from the front of the loom and as restrained from side swipe movement, and may be conven-

iently mounted on the feeler stand 4. In the present instance, the auxiliary feeler 20 extends through a bearing 21 at the rear portion of the feeler stand and its front end passes through a front bearing 22 which may be conveniently formed as a lug formed as part of or secured to the feeler stand 4. In the present instance, it is shown as secured to the feeler stand by means of a screw 23. Between the front bearing 22 and a collar 24 on the auxiliary feeler there is interposed a spring 25 which normally holds the auxiliary feeler 20 in its rearward feeling position, as indicated in Fig. 1.

In providing the rear bearing for the auxiliary feeler the slide 11 through which the main feeler extends may be made shorter than the corresponding slide of the Stimpson patent, as indicated in Fig. 3, so that the front bearing for the auxiliary feeler 20 may be constituted as a hole or holes passed through the guideway forming members at the rear of the feeler stand. This construction is found to be a convenient way of supporting the auxiliary feeler for movement towards and from the front of the loom while restraining it from lateral or side swipe movement, although other forms of bearings may of course be employed without departing from the true purpose of the present invention.

In the present instance, the auxiliary feeler 20 is shown as extending rearwardly into its feeling position to enter the shuttle and feel for the filling in a direction inclined to the longitudinal axis of the shuttle, and this is found to be a good form of the invention where the main side swipe feeler is of the inclined type, as shown. However, the invention contemplates mounting the auxiliary feeler 20 for movement towards and from the front of the loom while restrained from side swipe movement and such characteristics of the auxiliary feeler may be secured, even though the auxiliary feeler reaches rearwardly to its feeling position in a direction at right angles to the longitudinal axis of the shuttle.

Where the auxiliary feeler 20 is inclined, as shown, it may be desirable to provide its rear end portion with a movable filling engaging element such, for instance, as a roller 26, so that on the beat-up movement, the roller 26 will roll over the filling to a slight extent as the auxiliary feeler is moved frontwardly. In case the auxiliary feeler 20 is inclined, as shown, it may have sufficient play in its front and rear bearings to permit it sufficient movement without injurious effect to the filling, even though the roller 26 be not employed.

Between the main and auxiliary feelers there is a locking device which, as hereinbefore suggested, is effective to prevent side swipe movement of the main feeler should the

auxiliary feeler first engage the filling on a detecting beat, as, for instance, when a conical portion of filling is presented for engagement by the main feeler, but which is rendered ineffective to prevent such side swipe movement of the main feeler when the latter first engages the filling on a detecting beat.

The locking device, in the present instance, consists of a shoulder or hook 27 carried by the auxiliary feeler, and a reversely arranged shoulder or hook 28 carried by the main feeler. The hook 27 is shown as frontwardly pointed, while the hook 28 on the main feeler is shown rearwardly pointed, the effect being that when the two are engaged, as shown in Fig. 1, side swipe movement of the main feeler is prevented. Although the locking device as shown is found to be effective and practical, it of course may be varied to carry out the purpose of the present invention, and in the present case the shoulder 28 on the main feeler is formed as part or secured to a collar 29 which may be secured to the main feeler 7 in adjusted position by screws 30.

In accordance with the present invention, also, the filling engaging end portion 19 of the main feeler extends rearwardly a slight distance beyond the filling engaging end portion of the auxiliary feeler, so that should the cylindrical portion of the filling in the shuttle be presented for engagement by both feelers on a detecting beat, the main feeler will first engage the filling and be first moved frontwardly, as indicated in Fig. 2, to disengage the hooks 27 and 28 on the auxiliary and main feelers respectively, or in other words, render the locking device ineffective to prevent side swipe movement of the main feeler, because at such times the toothed engaging end 19 of the main feeler will sink into the filling mass and hold the main feeler from side swipe movement.

Only a portion of the lay and shuttle box at the feeler side of the loom are shown, because these parts may be of usual construction. The front wall 31 of the shuttle box is provided with an opening, as usual, for the entrance of the feelers, and similarly the front wall of the shuttle is provided with an opening 33 through which the feelers may extend on a detecting beat and feel for the filling in the shuttle. The filling is carried by a filling carrier or bobbin 34, and as hereinbefore noted, the filling 35 is wound upon the filling carrier or bobbin in conical layers from the head or base portion of the bobbin towards the tip, as usual. Under these conditions it will be apparent that at times the filling engaging end 19 of the main feeler will have presented to it a part of the conical wind and in the absence of any means to prevent it is liable to partake of its side swipe movement, but with the auxil-

iary feeler and locking device, substantially as hereinbefore described, such premature movement of the main feeler is prevented.

When a working supply of filling is present in the shuttle on a detecting beat, and a cylindrical portion of the filling is presented for engagement by both the main and auxiliary feelers, the main feeler will first engage the filling and be moved frontwardly relative to the auxiliary feeler to thereby render the locking device ineffective, as indicated in Fig. 2, whereupon the main feeler is freed to partake of its side swipe movement but is held from such movement by the toothed end of the feeler sinking into the filling, and this condition maintains during the entire beat-up movement of the lay, as indicated in Fig. 4. Should the conical portion of the filling wind on the filling carrier or bobbin be presented for engagement by the main feeler on a detecting beat while still a working supply of filling remains in the shuttle, the auxiliary feeler will first engage the filling, as indicated in Fig. 5, thereby causing initial frontward movement of the auxiliary feeler and maintaining the locking device effective to prevent side swipe movement of the main feeler, and this condition will continue until when the filling has been depleted to present a substantially cylindrical surface for engagement by both the main and auxiliary feelers, the main feeler will engage the surface within the shuttle in advance of the auxiliary feeler and render the locking device ineffective, thereby freeing the main feeler to its side swipe movement, as indicated in Fig. 6.

When the main feeler partakes of its side swipe movement, as indicated in Fig. 6, the slide 11 is caused to move laterally, substantially as in the Stimpson patent hereinbefore mentioned, and through the transmitter 16 call for a change of filling.

What is claimed is:

1. In a feeler mechanism for looms, the combination of a main feeler which is mounted to enter the shuttle in a direction inclined to the longitudinal axis thereof and for movement longitudinally along the filling carrier to call the change of filling, an auxiliary feeler mounted for independent movement towards and from the front of the loom and restrained from movement longitudinally of the filling carrier, and interlocking connections between the main and auxiliary feelers which prevent premature movement of the main feeler longitudinally of the filling carrier when the auxiliary feeler moves frontwardly on a detecting beat before the main feeler is moved and which are disengaged when the main feeler moves frontwardly before the auxiliary feeler is so moved.

- 4
2. Is a feeler mechanism for looms, the combination of a main feeler which is mounted to enter the shuttle in a direction inclined to the longitudinal axis thereof and for movement longitudinally along the filling carrier to call the change of filling, an auxiliary feeler mounted for independent movement toward and from the front of the loom and restrained from movement longitudinally of the filling carrier, and locking connections between the main and auxiliary feelers which are normally engaged when the main and auxiliary feelers are both in rearward feeling position and which become disengaged by frontward movement of the main feeler before such movement of the auxiliary feeler on a detecting beat and which remain engaged to prevent premature call for replenishment by the main feeler 10 when the auxiliary feeler is first moved frontwardly relative to the main feeler on a detecting beat.
3. Is a feeler mechanism for looms, the combination of two feelers which enter the shuttle on a detecting beat and feel for the filling, one of which is constituted as a main feeler mounted for movement longitudinally of the shuttle to call for a change of filling and the other of which is restrained from such movement, and a safety device comprising a lock normally positioned to prevent movement of the main feeler longitudinally of the shuttle on a detecting beat when both feelers are in rearward feeling 20 position and movable into unlocking position to permit such longitudinal movement of the main feeler when a cylindrical surface within the shuttle is engaged by both the main and auxiliary feelers on a detecting beat.
4. In a feeler mechanism for looms, the combination of two feelers which enter the shuttle on a detecting beat and feel for the filling, one of which is constituted as a main feeler mounted for movement longitudinally of the shuttle to call for a change of filling and the other of which is restrained from such movement, and locking connections between the main and auxiliary feelers which 30 become unlocked when both feelers meet the same cylindrical surface within the shuttle on a detecting beat and remain in locked position when the auxiliary feeler meets and is moved frontwardly by a surface within the shuttle before the main feeler meets a surface within the shuttle.
5. In a feeler mechanism for looms, the combination of a main feeler mounted for movement towards and from the front of the loom and in a direction longitudinally of the shuttle, an auxiliary feeler mounted for movement towards and from the front of the loom and restrained from movement longitudinally of the shuttle, interengaging 40 parts movable with the main and auxiliary feelers which become disengaged on a detecting beat when the main feeler meets the filling before the auxiliary feeler and which are engaged to lock the main feeler from premature movement longitudinally of the shuttle when the auxiliary feeler engages the filling before the main feeler.
6. In a feeler mechanism for looms, the combination of two feelers which enter the shuttle on a detecting beat and feel for the filling, one of which is constituted as a main inclined feeler mounted for movement longitudinally along the filling carrier by the frontward pressure upon it to call the change of filling and the other of which is constituted as an auxiliary feeler, and a safety device comprising a lock between the main and auxiliary feelers normally positioned to prevent movement of the main feeler longitudinally along the filling carrier 50 until the main feeler meets the filling in advance of the auxiliary feeler whereupon the main feeler is freed for movement longitudinally along the filling carrier.
7. In a feeler mechanism for looms, the combination of two feelers both of which enter the shuttle on a detecting beat to feel for the filling, one of which is a main feeler mounted for movement along the filling carrier to effect replenishment of filling and the other of which is an auxiliary feeler restrained from movement along the filling carrier, a locking device between the main and auxiliary feelers effective to prevent movement of the main feeler in a direction 60 longitudinally of the shuttle when the auxiliary feeler receives the frontward pressure of the filling in advance of the main feeler and is rendered ineffective to prevent movement of the main feeler longitudinally of the filling carrier when the main feeler receives the frontward pressure of the filling in advance of the auxiliary feeler.
8. In a feeler mechanism for looms, the combination of a main feeler which enters the shuttle to feel for the filling in a direction inclined to the longitudinal axis of the shuttle and is mounted for movement along the filling carrier to call for replenishment of filling, an auxiliary feeler which also enters the shuttle to feel for the filling, and a locking device comprising interengaging members on the main and auxiliary feelers rendered ineffective to lock the two feelers from relative movement during a detecting beat when the auxiliary feeler is the first to engage the filling and rendered ineffective to prevent such relative movement when the main feeler is the first to engage the filling.
- In testimony whereof, I have signed my name to this specification.
- ISAAC SNOW.
